OF NEW YORK, N. Y.

PHONOGRAPH LIGHTING SYSTEM.

1,400,694.

Specification of Letters Patent. Patented Dec. 20, 1921.

Application filed November 2, 1920. Serial No. 421,260.

To all whom it may concern:

Be it known that I, Ross M. G. PHILLIPS, a citizen of the United States, residing in the city and county of New Haven, State 5 of Connecticut, have invented a new and useful Improvement in Phonograph Lighting Systems, of which the following is a specification.

The object of my invention is to provide 10 a lighting system which lights the space where the record is placed to operate the phonograph and also the space in which the records are stored.

A further object of my invention is to 15 provide a lighting system which automatically lights the space where the record is placed for operation of the phonograph upon the opening of the door or cover of that space and without manual operation.

20 A further object of my invention is to provide a lighting system which operates to light the space in which the records are stored or kept by manual operation of the lighting system when it is desired to remove 25 or replace records from their places therein.

A still further object of my invention is 30 to provide a lighting system which automatically operates to shut off the light in both the space where the record is placed to operate the phonograph and the light in the space where records are stored upon the closing of the door or cover of the phonograph.

Still further objects of my invention will 35 be apparent from the following detailed description and the accompanying drawings which show embodiments of my invention and in which similar reference characters refer to similar parts.

40 Figure I. is a side view in cross section of the upper part of a phonograph showing the arrangement of my lighting system therein.

Fig. II. is a similar view to Fig. I. but 45 the top or cover of the phonograph is shown in raised or open position and the connections and switches are in the position in which my lighting system lights both the space in which records are placed to operate 50 the phonograph and the space in which records are stored.

Fig. III. is a front view of the upper-

part of a phonograph showing the arrangement of my lighting system therein with a front view in cross section of the automatic 55 means for turning the lights on and off.

Fig. IV. is a side view of the automatic switch used in my lighting system.

Fig. V. is a section of Fig. IV. on the lines A—A. 60

Fig. VI. is a view of the light used to light the space where the record is placed to operate the phonograph, the bulb being removed and the position and arrangement of the reflector is also shown. 65

Fig. VII. shows a different form of reflector which entirely surrounds the lamp and is adjustably mounted to throw the light to different parts, as required.

Fig. VIII. shows the position of lever 12 70 when switch 9 is closed and switch 10 is open.

An electric cord 1 is attached to a source of electric current and enters through an opening 4 the phonograph cabinet 2 which 75 has a cover 3 and space for storage of records 4. The cord 1 is connected to the posts 5 and 6 in the switchboard 7 which is comprised of any insulating material and is attached to the interior of the cabinet 2. 80

The post 5 is electrically connected to the bar 8 which is electrically connected to the knife blade switches 9 and 10. Mounted on the knife blade switch 9 is the shoulder 11 which is made of insulating material, such 85

as fiber, asbestos or other suitable material which carries the lever 12 extending above the cabinet 2 to the stop 13 of the cover 3. On lever 12 is moveably mounted the link 90

14 which is made of insulating material such as fiber, asbestos or other suitable material which is connected to knife blade switch 10. Electric cord 18 is electrically connected to post 15 and connection plate 16. Posts 6 and 15 are connected by wire 17 95

shown in dotted lines in Fig. IV. This wire is laid in a hollow groove in the sides of switchboard 7. Electric cord 19 is electrically connected to post 6 and contact plate 20. Cord 18 is connected by ordinary 100 electric means to lamp 21 which has a reflector 22. Lamp 21 is preferably mounted in the forward part of cover 3 and reflector 22 is arranged to throw the light toward sound

box 45. Cord 19 is connected to lamp 23 in the space for storing records. Lamp 23 is preferably mounted in the upper part of space 4.

5 Lever 12 has a notch 24 adapted to engage the pin 25 and is connected at 26 to tension spring 27, which is fixed at 28 by a nut or bolt.

10 Lever 12 may be placed in any of the three positions shown in Fig. IV.

If lever 12 is in position C, there is no connection between knife blade switches 9 and 10 and contact plates 16 and 20. Lever 12 is held in this position by pin 25 in notch 15 24. Lever 12 is placed in this position when the lighting system is not used.

If lever 12 is placed in position D, tension spring 27 tends to draw it upward and thus make a connection between knife blade switch 9 and contact plate 16. Stop 13 in cover 3 prevents this when cover 3 is down but when the cover is lifted, spring 27 causes this connection to be made. No contact will be made between knife blade 25 switch 10 and contact plate 20 because the link 14 is made short so as to prevent this.

If lever 12 is in position E, contact is made between knife blade switches 9 and 10 and contact plates 16 and 20 respectively. (See Fig. II.)

The current from a source of supply (not shown) flows through cord 1 to post 5 thence to knife blade switches 9 and 10. Knife blade switch 9 is in contact with plate 35 16. See Fig. VIII. In Fig. IV. the D position of lever 12 presumes lid 3 is closed down. If lid 3 is raised position D is modified by slight movement of lever 12 to the right of position D as shown the current 40 flows to light 21 and a return is made through posts 15, wire 17, post 6 and cord 1.

If contact is made by knife blade switch 10 lever 12 in position E (Fig. IV.) with contact plate 20, the current flows through 45 cord 19 to light 23 and returns through cord 19, which in my preferred form is a two-wire cord, post 6 and cord 1.

When the cover of the phonograph is closed, stop 13 presses lever 12 down (Fig. 50 I.) and breaks the connection between knife blade switch 9 and contact plate 16. When cover 3 is raised spring 27 draws lever 12 upward and makes a connection between knife blade switch 9 and contact plate 16 55 and lamp 21 is lighted. If it is desired to light lamp 23 in the record storage space 4, lever 12 is manually drawn forward to make the connection between knife blade switch 10 and contact plate 20, which results in 60 lamp 23 being lighted. Contact plate 20 is arranged to contact tightly with knife blade switch 10 and the friction created by the contact is sufficient to overcome the pressure of spring 27. Sufficient friction between 65 these parts may be created by mounting part

20 closely to part 7 but with sufficient freedom to receive knife blade switch 10 under pressure or by any of the other means in the art. When the cover 3 is closed stop 13 presses down lever 12 and thus breaks 70 the contact between knife blade switch 9 and contact plate 16 and knife blade switch 10 and contact plate 20. Stop 13 is positioned to operate on lever 12 in either the position shown in Fig. II. or in Fig. VIII. 75

In the construction shown in my preferred form, bar 8 is fastened to plate 7, parts 9 and 14 function as links to support lever 12. Part 9 is fastened to part 11 which is pivoted to the lower end of lever 12. 80 One end of part 9 is pivoted to bar 8. One end of part 14 is pivoted to lever 12 and the other to knife switch 10. The distance between the pivots of part 14 is shorter than the distance between the pivots of parts 9 and 11 and a line 85 connecting the pivots of parts 9 and 11 has a greater slope than the line connecting the pivots of part 14. Lever 12 is, in effect, supported by the two links parts 9 and 14. The lower end of lever 12 moves to the left (Fig. 90 IV.) as it is raised by spring 27. Spring 27 maintains the lever 12 against stop 25 and therefore lever 12 is tilted to the right when lever 12 is released by raising cover 3. With the proportion of the parts as shown considerable movement of lever 12 upwardly is required to close switch 16. Due to the tension of spring 27 the D position of lever 12 (Figs. I. and IV.) is an unstable position 95 and the lever must be held in this position and this is done by stop 13 in cover 3. The E position of lever 12 is further shown in Fig. II.

In the embodiment shown in Fig. VII. lamp 21 has the cylinder reflector 22 105 mounted in a support 29 which is attached by the hinge 30 to the plate 31 which is secured in the wall of the phonograph. This permits adjustment of the light to different parts of the space in which the record is 110 placed to operate the phonograph.

By my lighting system, when the cover or door of the phonograph is opened for the purpose of operating the same, a supply of light is secured by the opening of the door 115 or cover. This gives light to place records upon the turntable, locate needles, place needles in the sound box and adjust the needle upon the record. If a record is to be selected from the record cabinet or space 120 where records are stored, a supply of light may be secured in that place by moving the lever 12 forward. Meantime the supply of light in the upper part of the cabinet will be continued. When necessary steps to select a record and place same in operating position have been completed the supply of light in both the upper space and in the record cabinet are automatically cut off by the closing of the top of the phonograph. 130

Having described my invention what I claim and desire to secure by Letters Patent is:

1. In a phonograph lighting system, circuit wires, a lamp, a second lamp, electric circuits for said lamps, means to open and close the circuit of the first named lamp and to open the circuit of the second named lamp, actuated by a lid operated lever and 10 the circuit of the second lamp closed solely by manually rocking said lever.

2. In a phonograph, a lighting system supported therein, circuit wires, a lamp to light the space under the lid, a second lamp 15 to light the space where records are stored, electric circuits for said lamps, means to open and close the circuit of the first named lamp and to open the circuit of the second named lamp actuated by a lid operated lever, 20 the circuit of the second lamp being closed solely by manually rocking said lever.

3. In a phonograph lighting system, circuit wires, a lamp, a second lamp, independent circuits for said lamps, means to open 25 said circuits, actuated by a lid operated lever, means tending to hold the circuit of the first named lamp in closed position, the circuit of the second named lamp being closed solely by manually rocking the said 30 lever.

4. In a phonograph, a lighting system supported therein, circuit wires, a lamp to light the space under the lid, a second lamp to light the space where records are stored, 35 independent circuits for said lamps, means to open said circuits actuated by a lid operated lever, means tending to hold the circuit of the first named lamp in closed position, the circuit of the second named lamp being 40 closed by manually rocking the said lever.

5. In a phonograph lighting system, circuit wires, a lamp, a second lamp, electric circuits for said lamps, a common means to open and close said circuits, a spring tending 45 to maintain the circuit of the first named lamp closed, and the circuit of the second named lamp closed solely by manual movement of said common means.

6. In a phonograph, a lighting system 50 supported therein, circuit wires, a lamp for lighting the space under the lid of said phonograph; a circuit therefor, means to open said circuit comprising a lever, means tending to hold said lever in circuit closing 55 position, said circuit held in open position by the lid pressing upon said lever; a second lamp for illuminating the space where the records are stored; a circuit therefor, said circuit opened by said lever under pressure 60 of said lid and closed by manually rocking said lever.

7. In a phonograph, a lighting system supported therein, circuit wires, a lamp for lighting the space under the lid of said 65 phonograph; a circuit therefor, means to

open said circuit comprising a lever, means tending to hold said lever in circuit closing position, said circuit held in open position by the lid pressing upon said lever; a second lamp for illuminating the space where the records are stored; a circuit therefor, said circuit opened by said lever under pressure of said lid and closed by manually rocking said lever, and means to lock both said circuits in open position. 75

8. In a phonograph, a lighting system supported therein, circuit wires, a lamp to illuminate the space under the lid of said phonograph; a circuit therefor, means to open and close said circuit actuated by a lid 80 operated lever, means tending to hold said lever in circuit closing position, comprising a spring, said circuit held in open position by the lid pressing upon said lever; a second lamp to illuminate the space where the records are stored; a circuit therefor connected to said lever and closed by manually rocking said lever; said spring when the lid is raised moving said lever sufficiently to close the circuit of the first lamp but such movement being ineffective to close the circuit of the second lamp until said lever is moved manually in another direction, and the pressure of the lid upon said lever opening both said circuits. 85

9. In a phonograph, a lighting system supported therein, circuit wires, a lamp to illuminate the space under the lid of said phonograph; a circuit therefor, means to open and close said circuit actuated by a lid 90 operated lever, means tending to hold said lever in circuit closing position, comprising a spring, said circuit held in open position by the lid pressing upon said lever; a second lamp to illuminate the space where the records are stored; a circuit therefor connected to said lever and closed by manually rocking said lever; said spring when the lid is raised moving said lever sufficiently to close the circuit of the first lamp but such movement 95

being ineffective to close the circuit of the second lamp until said lever is moved manually in another direction, and the pressure of the lid upon said lever opening both said circuits, and both said circuits changed from 100 closed to open position by pressure of said lid upon said lever. 110

10. In a phonograph, a lighting system mounted therein, circuit wires, an adjustable lamp adapted to light the space immediately under the lid of said phonograph; a second lamp adapted to light the space where the records are stored, electric circuits for said lamps, means to open and close the circuit of the first named lamp and to open 120 the circuit of the second named lamp, actuated by a lid operated lever and the circuit of the second lamp closed by manually rocking the said lever. 125

11. In a phonograph, a lighting system 130

4

mounted therein, circuit wires, a lamp for illuminating the space under the lid, a circuit for said lamp, means for controlling said circuit, actuated by a lid operated lever, 5 means tending to hold said lever in circuit closing position by said lid through said lever; a second lamp to illuminate the space where records are stored, a circuit therefor, circuit controlling means connected to said 10 lever and said lever actuating the last named means to close the circuit of the second lamp solely when rocked manually.

12. In a phonograph, a lighting system supported therein, circuit wires, a lamp, a 15 circuit for said lamp, a second lamp, a circuit therefor, means to open and close said circuits, means tending to close the circuit of the first named lamp, means to restrain

the last named means, the first named means operated solely by manual movement to close 20 the circuit to said second lamp.

13. In a phonograph, a lighting system supported therein, circuit wires, a lamp, a circuit for said lamp, a second lamp, a circuit therefor, means to open and close said 25 circuits, means tending to close the circuit of the first named lamp, means to restrain the last named means, the first named means operated solely by manual movement to close the circuit to said second lamp, and the circuit of said lamp opened by said restraining means.
